UNITED STATES PATENT OFFICE.

EDWARD L. YOUNG, OF LITTLE YORK, ILLINOIS.

GIN POLE.

Application filed June 11, 1927. Serial No. 198,174.

This invention has reference to certain new and useful improvements in gin poles, and particularly to that type of gin pole especially useful in the raising and in the assembling in operative position of the wind-wheel and associated mechanisms on the tower of a windmill, and for repairing or disassembling such parts.

One of the objects of the present invention is to provide such a pole with a davit adapted to fit over the shoulder of a person, whereby the pole may be supported from the shoulder and the person's arms and hands left free to assist in ascending a tower to place the pole in working position, and in descending and removing such pole from the tower.

The invention has for a further object to provide adjustable means on the pole to adapt it to be secured in working position on towers of different makes and different constructions.

A further object of the invention is to provide such a pole with means to attach the pole to a windmill tower, including foot-rests to support a person, in the event and when it is inconvenient for such a person to stand on the tower platform.

Other and further objects will more fully appear in the description of the device.

That the invention may be more fully understood, reference is had to the accompanying drawings forming part of this description, illustrating a preferred embodiment of the invention, in which:-

Fig. 1 shows an elevation of the gin pole on a greatly reduced scale, partly in section, and illustrating by dotted lines a windmill tower and the working position of the pole thereon;

Fig. 2 is a side elevation of a part of the gin pole seen in Fig. 1;

Fig. 3 is a cross-section, in plan, as the same would appear if taken on the line 3—3, Fig. 2;

Fig. 4 is a perspective view of a preferred form of clamp;

Fig. 5 is a cross-section in plan as the same would appear if taken on the line 5—5, Fig. 2, and

Fig. 6 is a view similar to Fig. 5, except that the securing hooks are differently shaped.

Like characters of reference denote corresponding parts throughout the figures.

The windmill tower, which in itself is not new, I have chosen to show in dotted lines

and then only the extreme upper part thereof. These towers are generally constructed with metal standards *a*, preferably of angle iron, their upper parts converging and being secured together. There may be three (3) or four (4) such standards. As to this detail I am not much concerned, except as it affects the particular style of clamping hooks, see for instance Figs. 5 and 6. The former shows the tower with three standards and the latter with four standards. At a suitable point removed below the extreme upper end of the tower, such a tower is usually provided with a platform *b*.

The gin pole comprises preferably a tubular pole 1 of any suitable length. To its lower end is secured a transverse supporting and brace bar 2 provided with the longitudinal slots 3 disposed in and through said bar on opposite sides of the pole 1. Metal braces 4 connect the bar with the pole and where united with the bar provide foot-rests 5 and guards 6.

Slidably adjustable on the pole 1 is a transverse supporting and brace bar 7, preferably shorter in length than the bar 2, and said bar 7 is provided with the longitudinal slots 8 disposed in and through said bar on opposite sides of the pole 1. To one side of this bar 7 is inset a metal plate 9 having a curved seat to conform to the contour of the pole surface lying next thereagainst, and also to the same side of said bar is secured a metal strap 10 having an arcuate portion 11 adapted to extend part way around the pole and together with the curved seal of the plate 9 provides a bearing surface of metal for the metal pole and to strengthen the bar and prevent wear on the sliding surfaces of the bar. The strap 10 is provided with slots coinciding with the slots 8 in said bar 9, and the arcuate portion 11 of said strap has a boss through which is threaded an adjusting screw 12 for locking or securing the bar 7 in adjusted positions longitudinally of the pole 1 to properly position said bar 9 in its relation to the bar 2 when placing the gin pole in working position on a tower.

Clamping hooks 13 pass through the slots 3 in the bar 2 to engage with the standards *a* of the tower and may have the shape shown in either Fig. 5, or Fig. 6 and the ends of these hooks, opposite to their hooked ends are threaded so as to receive the thumb nuts 14 for locking or securing the clamping hooks to securely hold the bar 2 against the standards

of the tower. The tower structure may be such as will permit the bar 2 to rest on the platform *b* in which event a person may stand on the platform; but should the gin pole be secured to the tower and the bar 2 be elevated at a position above the platform, such a person may stand on the foot-rests 5, as will be understood.

To the bar 7 are slidably held the clamps 15. Such clamps include a channel strap 16 lying next adjacent one side free of the bar with portions overlying the opposite edges and to such straps are united by welding or otherwise the U shaped members 17, the leg portions of which are connected by pins 18 for the coupling thereto of a securing strap 19. The clamps 15 have bolts 20 which pass through the slots 8 in the bar 7 and slots in the strap 10 and to the threaded ends of said bolts 20 are connected the thumb nuts 21 for locking or securing the clamps 15 to securely hold the bar 10 against the standards of the tower. The hooks 13 on the bar 2 engage with the flanges of the angles of the standards *a*, whereas the clamps 15 are positioned so as to clamp the standards *a* of the tower therebetween, and the latter when so positioned are assisted by the strap 19, held by one post 18, passed about the standards *a* and caught to the other post 18, as will be understood. These clamps, as will appear, are of such design and so connected to the bar 10 that it is impossible for the clamps to cant on such bar.

To the upper end of the pole 1 is connected the davit 22. This davit has the stem portion 23 adapted for insertion into the open end of the pole and has a roller 24 on its inner end for a roller-bearing contact with the inner surface of the pole 1, when the davit is swung from one position to another, see full and dotted lines in Fig. 1. A threaded cap 25 may be employed to center the stem 23. The beam end of the davit has the curved portion 26 adapted to rest over the shoulder of a person to facilitate in such a person carry-

ing the same, leaving his arms and hands free to assist in climbing a tower to secure the gin pole in working position, and to descend from the tower with the pole. To the end of the davit may be connected a suitable tackle which, together with the necessary ropes may be used for raising the wind-wheel and associated parts or for lowering the same when repairing or dismantling the mill.

55

I have provided, in addition to the foregoing described elements a collar 27 slidably adjustable on the post 1 with a thumb nut 28 for securing said collar in adjusted positions. This collar has eyes or loops 29 for the connection of guy ropes, if desirable, for bracing the pole, should occasion require.

60

For the purposes described, my gin pole is convenient and easy of manipulation and will facilitate the easy and quick erection of a wind-wheel and associated parts of a windmill and for the easy, quick and convenient dismantling or repairing of the same. Said gin pole, including as it does adjustably attaching means, is adapted for practicable application to windmills of different structure and design and when once in working position is held firm so that raising and lowering of parts can be accomplished with little or no difficulty and with little or no chance of danger.

70

What I claim is:—

A gin pole comprising a pole member, a transverse supporting bar secured to one end of said pole, bracing means between said bar and pole forming foot-rests at the outer ends of said bar, securing members longitudinally adjustable on said bar, a second transverse supporting bar longitudinally adjustable on said pole, means for securing said bar in different positions on said pole, bracing clamps longitudinally adjustable on said last mentioned bar and a fastening strap cooperating with said clamp.

85

In witness whereof, I have hereunto affixed my hand this 8th day of June, 1927.

EDWARD L. YOUNG.
